UNITED STATES PATENT OFFICE.

EMMET P. GRAY, OF DETROIT, MICHIGAN.

MUFFLER-VALVE.

1,299,326.

Specification of Letters Patent.

Patented Apr. 1, 1919.

Application filed October 8, 1917. Serial No. 195,256.

To all whom it may concern:

Be it known that I, EMMET P. GRAY, a citizen of the United States, and residing at Detroit, in the county of Wayne and 5 State of Michigan, have invented a new and Improved Muffler-Valve, of which the following is a specification.

This invention relates to means for using or disposing of the burnt gases of automobile engines so that they will have the least 10 objectionable effect on the power of the engine, and its object is to provide a muffler valve which may connect the muffler to a heating system for the body of the automobile or which may be used as a cut-out.

This invention consists in combination with a muffler formed of a chamber to receive the exhaust and means to conduct the exhaust thereto, of a head for the chamber 20 and a rotatable valve body connected to said head, and a plurality of other chambers, one within the other, surrounding the first and adapted to receive the exhaust therefrom, said head having a constantly 25 open discharge passage connecting to the outer chamber. This invention further consists in the details of construction illustrated in the accompanying drawing and particularly pointed out in the claims.

30 In the accompanying drawing, Figure 1 is a side elevation of the muffler and valve body. Fig. 2 is an elevation taken from the left in Fig. 1. Fig. 3 is a similar elevation taken from the right. Fig. 4 is a central longitudinal section parallel to the plane of Fig. 1.

Similar reference characters refer to like parts throughout the several views.

The muffler shown in the drawing is of 40 the general character shown in my Patent No. 820,566, dated May 15, 1906, and consists of three drums or chambers 1, 2 and 3, the inner and outer being each preferably formed of two thicknesses of sheet 45 steel with a layer of asbestos between them. The inlet end or front head 4 may be formed with circular flanges 5, 6 and 7 to center these drums.

The outlet end or rear head 8 may also 50 have centering flanges 9, 10 and 11, and is formed with a nozzle 12 to receive the pipe 13 which, however, may be omitted if desired. This nozzle connects to the chamber between the drums 2 and 3. The head 55 4 may be formed with a neck 14 to receive the exhaust pipe 15 through which the burnt

gases from the engine enter the inner drum 1. From here the gases pass through the holes 16 in the rear end of this drum into the chamber between the drums 1 and 2, in 60 which space the gases pass forward to the holes 17 in the drum 2 and through these holes into the chamber between the drums 2 and 3, and thence rearward to the nozzle 12. 65

Exhaust gases are caused to pass into radiators in the bodies of automobiles to heat the bodies. These radiators usually connect to the pipe leading from the engine to the muffler or to the discharge opening 70 of the muffler, in which latter case the gases have been cooled because they have been forced to pass through all the compartments of the muffler. This results in excessive back pressure and is very undesirable. 75 Taking the gases from the exhaust pipe before they get to the muffler results in a noisy heater which responds to the pulsations of the engine. It also results in serious back pressure. 80

In the present case, a circular flange 20 is formed on the rear head 8 to receive one end of the valve body 21, preferably formed with a groove 22 to receive the screw 23 carried by this flange 20, whereby the part 21 is held 85 in position. A valve stem 24 carries the valve 25 and a crank arm 26 on the stem positions the valve. A spring 27 may be employed to hold the valve closed and the body 21 may have an extension 29 to receive 90 the pipe 30 that connects to the radiator. This pipe 30 is preferably a flexible metal tube. Bolts 31 secure the heads and drums together. 95

As this is a stock construction, provisions 95 may be made for adapting it to various types of automobiles and various locations of radiators by forming the valve body 1 with a bend so that the pipe 30 may extend at an angle to the axis of the muffler. This 100 also permits the valve to be used as a cut-out in cities where direct exhaust downward toward the roadway is forbidden, the method of mounting the valve body permitting the exhaust to be directed at any desired angle. 105

As the valve 21 connects to the inner chamber into which the gases flow directly from the exhaust pipe 15, and where the pulsations are virtually taken out of the gases, the back pressure caused by the radiators when 110 in use will be less than that normally caused by the muffler, particularly because the noz-

zle 12 is always open. Because of the straight path to the atmosphere from the engine through the pipe 15, the inner chamber of the muffler, the valve body 21, the 5 pipe 30 and the radiator, this back pressure must be less than when the gases pass through the muffler in the usual manner, for otherwise the gases will pass through the muffler as before. When the valve 21 is used 10 as a cut-out, a straight path is provided for the gases from the rear end of the exhaust pipe 15.

I claim:—

1. In a muffler valve, the combination with 15 the head of a muffler having an opening connecting to that portion of the muffler which receives the direct exhaust of the engine, said head having a circular flange around the opening, a valve body rotatably mounted in 20 said flange, and a discharge pipe attached to said valve body and extending at an oblique angle from the head, which pipe may be caused to extend at any desired angle by turning the valve body.
- 25 2. The combination with a muffler having circular heads and drums within each other,

said heads having inlets and outlets connecting into the chamber formed by the inner drum, one of the heads having a constantly unobstructed outlet connecting with the 30 chamber within the outer drum, and a valve body rotatably mounted in the outlet connecting into the inner chamber, said valve body having an angular discharge pipe which may be pointed in any desired direction by rotating the valve body. 35

3. The combination with a muffler having an inner chamber and a plurality of chambers surrounding said inner chamber and connecting therewith by means of holes in 40 their walls, means to convey the exhaust of an engine to the inner chamber, a constantly unobstructed and invariable conduit for conducting the gases from the outer chamber to the atmosphere, a rotatable valve body connecting to the inner chamber, and an adjustable valve in said body to control the flow of 45 gases therethrough, said body having an angular discharge pipe which may be pointed in any desired direction by rotating the 50 valve body.

EMMET P. GRAY.
